UNITED STATES PATENT OFFICE

WILLIAM C. HOLBROOK, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 31, 1929. Serial No. 382,461.

This invention relates to refrigerating apparatus and more particularly to the cabinet structure of the refrigerating apparatus.

An object of this invention is to provide a cabinet of the domestic mechanical refrigerating type which cabinet is provided with a metal framework.

Another object of the invention is to provide a supporting structure for the interior parts of the refrigerator cabinet that shall be both strong and yet graceful in outline.

Another object of the invention is to provide a metal framework and framework parts that are very strong and yet without bulk.

15 Further objects of the present invention will be apparent from the following description, reference being had to the accompanying drawings, wherein a preferred form of the invention is clearly shown.

20 In the drawings:

Fig. 1 is a perspective view of a preferred form of frame work for a refrigerator cabinet.

Fig. 2 is a perspective view of one of the 25 bars or irons of the frame work before being put in shape.

Fig. 3 is a perspective view of the bar of Fig. 2 with its end bifurcated.

Fig. 4 is a perspective view of a corner piece 30 of the frame formed preferably by three members with their bifurcated ends as disclosed in Fig. 3 butt welded together.

Fig. 5 is a vertical cross section of a cabinet embodying features of this invention.

35 Fig. 6 is a vertical cross section of the cabinet taken transversely to that of Fig. 5.

Fig. 7 is a horizontal cross sectional view taken on line 7—7 of Fig. 5.

40 Due to the scarcity of wood and also to its moisture absorbing properties it is highly desirable to eliminate from the construction of cabinets used for refrigerating apparatus unnecessary wood elements. It has hitherto been the custom to use wood for the frame

45 work parts of a refrigerating apparatus. Accordingly it is one of the objects of this invention to substitute a metallic frame work for the wooden framework of the prior art.

50 If desired the wood could be entirely eliminated but it might be desirable to retain cer-

tain wood structure on account of its excellent combination of insulation and strength at such places where such combination is highly desirable, such as the door jambs.

While metal parts are used in the frame 55 work it is desirable that they should have considerable strength without bulkiness or costly assembling operations. Accordingly it is another object of this invention to provide a metal framework that will not only 60 be strong but which will also be easy to assemble and one upon which can be assembled a cabinet graceful in outline.

A cabinet embodying features of this invention may comprise a frame work composed of the elements or members 10 to 21 inclusive which will be of a construction and assemblage to be more fully described hereinafter. This cabinet may be provided with 65 a door jamb of strong non-conducting material such as wood and generally designated as 22. Secured within the frame work may be a box like sheet metal food compartment lining 23 which may be provided with a door opening generally designated as 24. The lining 23 may be secured in any suitable manner with its edge adjacent the door opening in the door jamb 22. Preferably the edge of the lining about the door opening may be secured to the door jamb as by being nailed 70 along the off-set portion under a molding 34 as disclosed in Fig. 6. A door jamb 22 may if desired be placed within the metal frame work and attached thereto as illustrated in Fig. 1.

Within the food compartment may be placed a cooling unit 27 of a mechanical refrigerating system and this cooling unit may be an evaporator provided with a float valve control and with a refrigerating liquefying unit such for instance as that described in the patent to R. G. Osborn 1,556,708 issued October 13, 1925.

If desired the evaporator 27 may be partly 95 enclosed by a partition 28 secured to the sides of the lining. This partition may be altho not necessarily of the type disclosed in the application of Francis E. Stevenson S/N 257,999 filed Feb. 29, 1928. Under the evaporator may be placed a drain pan 29 and a 100

drain pipe 30 leading to a loop 31 and discharging into a pan 32 slidably supported on brackets 33.

If desired the lining 23 having been set 5 cured to the door jamb 22 which is in turn firmly fastened to the front part of the metal frame work, the outer surface of the lining may be coated with bituminous cement such as is known in the trade by the name of hydrolene. While the surface is still hot the sides of insulation 35 which may be cork board or rock cork may be applied to the lining and are thus cemented thereto when the cement cools. After the insulation has been 10 secured to all of the sides or lining or while it is being secured the outer surface of insulation may be rendered substantially air tight as by placing an air tight cover of hydrolene on the outer surface of the insulation.

20 The outer panels 36 may be secured in any suitable manner. If the outer panels are steel with a porcelain enamel coating, it may be desirable to interpose between the panels of the framework a suitable padding 37. This padding may be soft and may be of card board or of masonite or any other desired type of pliable board. This may be secured to the metal frame work or to the outer coat or hydrolene either independently of the panels or 25 by the same means which secures the panels in place. The outer panels may be of any suitable construction and may be if desired of the type shown in the application of Henry P. Braeutigam and Wm C. Holbrook S/N 35 257,989 filed Feb. 28, 1928, to which reference is made if necessary for a full disclosure of the panels. These panels are all provided with longitudinal flanges and are substantially independently removable from the cabinet in the manner disclosed in the said application.

The upright members 10 to 13 and the horizontal members 14 to 21 may be of any desired shape such as the ordinary angle iron. 45 It is desirable however to have instead of the usual abrupt corner angle, that these members be transversely curved as disclosed in Fig. 2. If desired a more rounded curve may be used than that disclosed in Fig. 2. 50 In order to provide a very strong but very graceful construction the ends of the members are preferably formed as disclosed in Figs. 3 and 4. The end 39 of these members and preferably all of them is bifurcated as disclosed in Fig. 3 by spreading the ends down a portion 40 of its longitudinal direction and thus providing two bifurcated portions 41, 42. These bifurcated portions 41 and 42 are preferably spread apart so that they are 60 slightly curved away from the longitudinal direction of the member.

Three of these members, preferably similarly bifurcated, are placed with their longitudinal directions substantially 90° from one 65 another as disclosed in Fig. 4. Take for in-

stance the right hand front upright or vertical member 11 and the front top or horizontal member 14 and the side top or horizontal member 19 having their longitudinal direction in the frame work at 90° to one another. The member 11 has one of its bifurcated portions 42 adjacent a bifurcated portion 41' of the member 14 and its other bifurcated portion 41 adjacent the end of the bifurcated portion 42" of the member 19. Similarly member 14 has its bifurcated portion 42' adjacent the bifurcated portion 41" of the member 19. These three members are joined together by means of their adjacent portions and a preferred joint between them is that of butt welding each bifurcated portion to the adjacent bifurcated portion of the adjacent member as disclosed in Fig. 4.

In this manner the members 11, 14 and 19 are structurally integral united and any strain or stress upon one member will be resisted by the other members. For instance any shock delivered upwardly along the member 11 will be divided along the bifurcated portions 41' and 42" and communicated to the members 14 and 19 at least partly longitudinal of the material and thus be resisted more than if it was merely communicated transversely to the members 14 and 19.

The front panels 44 of the cabinet are preferably curved as at 45 in a curve substantially similar to the curved part 38 of the vertical corner posts 10 and 11. Furthermore the side panels are also curved as at 46 similar to the curve on the rear vertical corner posts 12 and 13. This curving of both the frame work and the outer panels makes a very graceful as well as strong construction of the refrigerator cabinet.

It is obvious that any changes could be made in the construction of the preferred form without departing from the spirit of the invention. While the metal framework as disclosed in Fig. 1 is preferably composed of members or bars butt welded to one another at their ends it might be preferable to use three short members such as the end portions of 11, 14 and 19 disclosed in Fig. 4 and butt welded or otherwise connect these into the strong but light and graceful joint disclosed. After this corner piece has been formed the longer connecting bars extending from one corner to another may be welded or otherwise secured to these shorter corner members. While this construction may require an additional welding or riveting yet it might be preferred from a quantity production standpoint as it would probably take less skill in assembling a small group of connecting bars and corner pieces than to make a unit assembly as disclosed in Fig. 1.

Accordingly there has been disclosed a refrigerator cabinet having a very graceful but light and strong supporting structure for its interior elements. Furthermore the cor-

ners of the frame work are such that they are fully adapted to withstand any shock or blow and to structurally resist this shock or blow in a manner superior to the usual 90° corner construction. The correspondingly shaped outer panels also add to the grace of the assemblage.

While the form of embodiment of the invention as herein disclosed constitutes a preferred form, it is to be understood that other forms might be adopted, all coming within the scope of the claims which follow.

What is claimed is as follows.

1. A frame for refrigerating cabinets comprising a plurality of transversely curved angle iron members with their longitudinal directions substantially at right angles to one other, said angle iron members being bifurcated, the bifurcated portions of said members being bent towards the bifurcated portions of other members and attached thereto.

2. A three way corner piece for refrigerating cabinets comprising a plurality of transversely curved members with their longitudinal directions substantially at right angles to one another, said members being bifurcated, the bifurcated portions of said members being bent towards the bifurcated portions of other members and attached thereto.

3. A refrigerator cabinet including a metal frame work comprising a plurality of horizontally disposed metal members, a plurality of vertically disposed metal members, some of said members being bifurcated, the bifurcated portions of said members being transversely bent towards the other of said members and attached thereto to form a curved corner.

40 In testimony whereof I hereto affix my signature.

WILLIAM C. HOLBROOK.
